CONVECTION HEATER

Martin J. Whelan, Glendale, Calif.

Application April 12, 1944, Serial No. 530,719

8 Claims. (Cl. 257—134)

This invention relates to a convection heater. Heretofore it has been the practice, in constructing heaters of the kind to which this invention pertains, to install the heat-radiating part in the bottom portion of the cabinet. This results in a disadvantage when it is desired to convey the heating fluid through bendable metal pipes which are directed upwardly into the cabinet, because it prevents making such pipes long enough so that they can endure being repeatedly flexed as is required in moving the cabinet out from and back into a wall recess provided for it. By this invention the heat generating portion of the structure is located in the upper portion of the cabinet, thus overcoming the above mentioned defect.

Among the objects of the invention are to provide, for house heating, a heater which is better adapted for being installed within one of the walls of a room, where it will be out of sight when not in use and will in no wise detract from the neat appearance of the room; to provide a heater which will not interfere with the thorough cleaning of the room at any time; to provide a heater of a more space-economizing character which will always be neat in appearance whether in use or out of use; and to provide a house heater contained in a cabinet of an improved construction which may be more conveniently moved manually from its retracted, concealed position to the extended position which it occupies when the heater is in use.

A more specific object of the invention pertains as has already been indicated, to the provision of a wall heater of the extensible type which may be moved to and from an alcove therefor in the wall, the heater being of that type where-in metal pipes are used to convey steam through them or other heating fluid, said pipes being slightly flexible and the arrangement of the pipes being such that ample length of pipe is provided for the part of the pipe that is flexed so that, during the movement of the heater to and from its retracted position the required bending of the pipe will be distributed over a sufficiently great length of pipe to avoid danger of weakening or breaking the pipe as a result of being repeatedly flexed.

Other objects, advantages and features of invention will hereinafter appear.

Referring to the accompanying drawing, which illustrates what is at present deemed to be a preferred embodiment of the invention,

Fig. 1 is a front elevation of the device as in-

stalled for use, one side portion thereof being broken away to disclose interior construction.

Fig. 2 is a vertical section on angular line 2—2 of Fig. 1.

Fig. 3 is a plan view of the heater, the same being shown in the retracted position in the left portion of the view and in the extended position in its right hand portion. The wall is shown sectioned on line 3—3 of Fig. 1.

10 Fig. 4 is a vertical section, showing on an enlarged scale the guiding means which govern the movement of the heater from and to its retracted position, the angular line 4—4 on Fig. 3 indicating the plane of section.

15 Fig. 5 is a vertical section on line 5—5 of Fig. 3. Referring in detail to the drawing, 6 designates in a general way a portion of the wall structure of a room upon which the heater is mounted. In said wall portion a rectangular alcove is formed having surfaced studding 7 at its sides, a back wall 8, a top wall formed by a window sill 9 and having its bottom formed by the floor 10 of the room. Through said floor 10 is cut an elliptical opening near each side of 20 the cabinet, the major axes of said openings extending transversely of the aforesaid alcove. Within each of said openings is fitted a spacious elliptical ring or sleeve 11 the purpose of which will presently appear.

25 30 In the upper portion of the alcove of the wall is a sheet metal lining member 12 having a top wall portion 12a, a back wall portion 12b and end wall portions 12c. Outside of all of these wall portions of said lining member is a layer 12d of asbestos which prevents the adjacent portions 35 of the wall from becoming overheated by the heater element presently to be described.

35 The cabinet structure, which is capable of extension and retraction with respect to the alcove 40 by means of the handle 13, comprises a front wall or panel portion 14 and end walls 15 so constructed as to enclose a rectangular space which is open at the top, bottom and back.

45 A pipe structure is provided which comprises a straight horizontal top run or pipe 17 at each end of which is an elbow 18, one of said elbows connecting one end of the horizontal pipe with an upstanding fluid intake pipe 19, which is directed upwardly through the already mentioned sleeve 11 at its side of the structure, the opposite end of said pipe 17 being connected by means of the other elbow to an upstanding fluid outlet pipe 19a correspondingly positioned at the opposite side of the structure. It will be observed that 50 when the cabinet is in use its end walls 15 con-

ceal the upstanding pipes 19, 19a thus contributing to the neat appearance of the device.

The horizontal top pipe 17 carries a series of rectangular heat radiating fins 20, said fins being in a closely adjacent relation to each other and being desirably equally spaced apart in respect to the length of the pipe as shown in the drawing. Each of these fins is provided with a central apertured portion which is fitted closely around the pipe, the fins being secured to the pipe by welding or any other well known desired means.

The horizontal top pipe 17 has each of its end portions extending through one of the corner portions of an approximately triangular sheet metal bracket 17x which has along its opposite side an attaching flange 17y welded or otherwise secured to the back side of the front wall 14 of the cabinet. Said bracket flanges are shown directed away from each other, the body portion of each bracket abutting against the heat radiating fin at that end of the series. Along the back face of the upper part of the front cabinet wall 14 extends, from bracket to bracket, a layer of asbestos 14a, there being a slight space between the fins and said wall portion, which space is occupied by said asbestos layer to prevent the front wall of the cabinet from becoming undesirably hot. It is desirable to provide a backward bend in the pipe structure at each end of the horizontal pipe 17, and as this must be done without interfering with the mounting of the fins 20 upon the pipe 17, each of the pipes 19 and 19a is provided near its upper end with a back bent portion B which is fitted into the already mentioned elbow 18 at its side of the cabinet. When the cabinet is drawn out from the alcove by means of the handle 13 the flanges or brackets 17x engage the pipe structure shown to force it forwardly.

Below the extensible cabinet structure is a base board 21 which is so positioned that when the cabinet is in its retracted position, said base board will form a downward continuation of the front panel 14 of the cabinet, and at the same time a header 21' above the cabinet will form an upper continuation of the upper part of said panel 14. By painting or papering the panel 14 in the same manner as the adjacent portions of the wall the appearance of the wall will not be noticeably altered when the cabinet is in its retracted position.

Describing now the means for guiding the movements of the cabinet from and to its retracted position, as generally indicated at 22 in Fig. 1, but shown on a larger scale in Figs. 4 and 5, at each of the four corner portions of the alcove there is provided a horizontally extending C-shaped guide plate 23 which is secured to the adjacent wall portion of the alcove by screws 24 one of which is shown in Fig. 5. When thus secured in place each of these guide plates is prepared to receive a rail 25 which is T-shaped in cross section, said rail having a web 25' which extends through the open side of the guide plate 23 and having a head flange 25" consisting of a strip which extends horizontally as to its length and vertically as to its width within said guide plate, the lower edge of said strip 25" resting slidably upon the lower inner surface of said guide plate. Welds 26 are shown whereby the stem portion of said T-shaped rail is secured to the adjacent end wall 15 of the cabinet. Stop lugs 28 are carried by the rear edge portion of each end wall of the cabinet to cooperate with

upper and lower flanges 29 of the guide plate 23 to limit the outward movement of the cabinet, the cooperative relations of said lugs and flanges is shown in Fig. 4.

5 In the operation of the device the attendant does not have to open or close any valves, and need only pull out upon the handle 13 and thereby withdraw the cabinet from the alcove so that the air after entering the opening beneath the bottom of the extended cabinet, will ascend to the upper portion thereof where it will move over the surfaces of the heated fins and, by convection, convey the heat radiated from them out into the room.

10 15 When the cabinet is pushed back into the wall, the circulation of air across the fins is stopped, and so is the radiation of heat from them. In the heating operation which takes place when the cabinet is drawn out from the wall, the air enters the open lower end of the cabinet, as indicated by the arrows in Fig. 2 and after being heated by the fins in the upper portion of the cabinet passes out into the room.

15 20 The upstanding pipes 19 and 19a are desirably of copper or of a similar soft, bendable metal so that they may be repeatedly bent the required amount without injury, and also will remain in the adjusted position both after extension and retraction of the cabinet. By comparing with 25 30 each other the full line and dotted line positions of these pipes as shown in Fig. 2, it will be seen that each pipe may rise slightly as it is drawn forwardly and descend slightly as it is pushed back, thus permitting the required horizontal, rectilinear movement of the fin-carrying pipe 17.

35 40 It should be understood that the present disclosure is for the purpose of illustration only and that this invention includes all modifications and equivalents which fall within the scope of the subject matter claimed.

40. What is claimed is:

1. In a heater of the kind described, a cabinet insertable into a wall alcove therefor, guide means to guide said cabinet while being moved horizontally from and to a retracted position in

45 50 relation to said alcove, heat radiating means mounted in the upper portion of said cabinet, and deflectable metal pipes extending upwardly through the bottom of said alcove and thence upwardly to said heat radiating means to convey a heating fluid thereto.

55 60 2. The combination, with a vertical room wall having therein an alcove which opens into the room near the floor thereof; of a cabinet normally occupying said alcove, guiding means intervening between said cabinet and side portions of said alcove to guide said cabinet while being moved horizontally from and to a retracted relation to said alcove, heating means mounted in the upper portion of said cabinet, and deflectable metal pipes extending upwardly through the bottom of said alcove and thence upwardly to said heating means to convey a heating fluid thereto,

65 70 60 65 metal pipes passing through a hole in the bottom of said alcove sufficiently large to allow a material horizontal movement of the part of the pipe within said hole when the cabinet is moved as aforesaid.

75 70 65 3. The combination, with a vertical room wall having therein an alcove which opens into the room near the floor thereof; of a cabinet normally occupying said alcove, guiding means intervening between said cabinet and side portions of said alcove to guide said cabinet while being moved horizontally from and to a retracted re-

lation to said alcove, heating means mounted in the upper portion of said cabinet, said heating means including a pipe extending in a generally horizontal direction in the upper part of said cabinet, an upstanding fluid supply pipe in one side portion of said alcove positioned to convey heating fluid to one end portion of said horizontal pipe, and an upstanding fluid outlet pipe in the opposite side portion of the alcove positioned to convey the fluid from the opposite end of said horizontal pipe, said upstanding pipes being sufficiently deflectable to follow said cabinet during its movement from and to a retracted position in relation to said alcove.

4. In a heater of the kind described, a structure containing an upstanding alcove the height and width of which is great in comparison to its front to back dimension, a cabinet housable within said alcove, guide means in said alcove for said cabinet along which it is horizontally movable from and to a retracted position in relation to said alcove, heating means within said cabinet comprising a pipe in the upper part thereof extending in a generally horizontal direction, and upstanding deflectable pipes communicating with the opposite ends of said horizontal pipe, said upstanding pipes leading up into said alcove through the bottom thereof.

5. In a heater of the kind described, a structure containing an upstanding alcove the height and width of which is great in comparison to its front to back dimension, a cabinet housable within said alcove, guide means in said alcove for said cabinet along which it is horizontally movable from and to a retracted position in relation to said alcove, heating means within said cabinet comprising a pipe in the upper part thereof extending in a generally horizontal di-

rection, and upstanding deflectable pipes communicating with the opposite ends of said horizontal pipe, said upstanding pipes leading up into said alcove through the bottom thereof, said cabinet having wall portions which conceal said upstanding pipes when the cabinet is withdrawn from its aforesaid retracted position.

6. The subject matter of claim 1, and there being a base-board upstanding from the floor of 10 the room along the front side of said alcove, and said cabinet having an open lower end which is positioned forwardly of said base-board when the cabinet is in its extended position, to admit air from the lower portion of the room into said open 15 lower end of said cabinet, said base-board forming a downward continuation of the front wall of the cabinet when the latter is in its retracted position.

7. In a heater of the kind described, a cabinet 20 insertable into a wall alcove therefor, guide means to guide said cabinet while being moved horizontally from and to a retracted position in relation to said alcove, heat radiating means mounted in the upper portion of said cabinet, a horizontal pipe forming a support for said heat radiating means, deflectable pipes extending upwardly through the bottom of said alcove and communicating with opposite end portions of 25 said horizontal pipe to convey heating fluid to and from said horizontal pipe, and brackets secured interiorly to the upper portion of said cabinet and also secured to said horizontal pipe.

8. The subject matter of claim 7, and said 30 brackets consisting of plates having apertures 35 through them within which said horizontal pipe is fitted.

MARTIN J. WHELAN.
